GRINDING MILL

Application filed October 28, 1929. Serial No. 402,891.

This invention relates to grinding mills, it relating more particularly to mills which employ a rotary grinding element which cooperates with a stationary grinding element supported by the casing of the mill and in which the direction of rotation of the rotary grinding element may be reversed. One of the special features to which the invention relates is the provision of means for reversing the position of the stationary grinding element with relation to the rotary grinding element as well as the feeding and discharge devices to correspond with the desired direction of rotation to adapt the mill to different conditions of installation. Another feature relates to the construction and arrangement of the discharge devices for the ground material to adapt such devices to the most efficient operation.

In the manufacture of mills of this type it is customary to assemble the grinding elements and the feeding and discharge devices to adapt them to a given direction of rotation of the rotary grinding element. Such an assembly of the parts however is not suitable for all desired installations, making it necessary in many cases to build special mills adapted to the installation desired.

One of the objects of this invention is to so construct the mill that the relation of such parts as the grinding elements and the feeding and discharge devices may be readily altered at the place of installation so that the mill may be assembled in a uniform manner at the factory in a way suitable for a majority of installations, but be readily altered at the place of installation to adapt the mill to a desired installation.

Another object of the invention is to improve the construction of the discharge device so that these devices may not only be adjusted to the desired installation but also so constructed and so adjusted with relation to the grinding mechanism as to secure the most efficient discharge of different kinds of ground material.

In the accompanying drawings:

Fig. 1 is an end elevation of, in the present case, a hammer mill in which are incorporated the improvements to be described.

Fig. 2 is a fragmentary end elevation of the same machine, the machine having been converted for the opposite direction of rotation.

Fig. 3 is a fragmentary end elevation of 55 a portion of a main side frame.

Fig. 4 is a front elevation of the machine.

Fig. 5 is an elevation of a detail.

Fig. 6 is an elevation, partly in section 60 of a detail.

Referring to the drawings, in the present case the rotary grinding element is shown in the form of hammers 1 pivotally mounted on rods 2 which are secured to disks 3, the disks being spaced apart to provide for the usual 65 loose mounting of the hammer; the disks 3 being keyed to a shaft 4 which is rotatably mounted in bearings 5 secured to end plates 6 which constitute the main frame of the machine. A reversible electric motor M is 70 shown in direct connection with the shaft 4. The end plates are secured one to another at the proper distance apart by front and rear plates 7 and 8, preferably by welding; the end plate 6 and plates 7 and 8 forming 75 a lower stationary rectangular casing open at the top and bottom.

Cooperating with the rotary grinding element is a stationary grinding element in the form of a curved breaker plate 9, whose lowermost edge terminates near the horizontal center line and in close proximity to the ends of the hammer when extended radially. The breaker plate is secured within an upper movable casing, open at one side and the bottom, this movable casing being formed of plates 10 which form the ends and a curved plate 11 which forms one side and the top. This movable casing is arranged to be hingedly mounted on either side of the lower 80 casing and to that end the lower casing has ears 12 secured to both upper corners of each end plate 6, the ears of each end plate being arranged at equal distances from the vertical center line of the mill. These ears carry 85 rods 12' and the lower corner of each end plate 10 of the upper casing, adjacent the open side thereof is perforated to receive either end of the rods, depending upon which 90 way the upper casing is positioned. The 95

upper casing is secured to the lower casing by 100 the rods 12' and the ears 12.

closed side of the upper casing is provided with a suitable latch L to engage with the adjacent rod 12' to hold the upper casing in closed position. The upper casing carries a feed trough 13 which projects into the open side thereof, the inner end of this trough being supported by a rod 13' supported by the end walls 10 and the outer end of the trough being supported by pivoted links 13".

As the grinding of the material is accomplished by the proper co-action of the hammers and the breaker plate, it will be seen that the breaker plate must be positioned in accordance with the direction of rotation of the hammers and that the feed trough must be likewise so positioned. The usual method of assembly of the parts is illustrated in Fig. 1. If, however, the installation must be such that the material should be fed from the opposite side of the machine, the upper casing is reversed by hinging it to the rod 12' on the left hand side of the machine as shown in Fig. 2 which changes the location of the breaker plate with respect to the hammers and also to the location of the feed trough; the direction of rotation of the hammers being reversed by suitable changes in the motor in a well known manner. It should be stated that the upper casing is hinged to the lower casing for the purpose of permitting access to the interior of the mill when desired.

The ground material is conveniently removed from the machine and conveyed to a suitable point of storage (not shown) by means of an air current set up by a fan 14 which is, in the present case, secured to the outer end of the shaft 4. The fan casing 15, Fig. 6, is a simple element, composed of sheet metal ends 16 and a connecting sheet metal member 17 curved to a volute-like form and further provided with a bolting flange 18 by which it is attached to the flange of a discharge conduit 18'. By reason of similar bolt spacing in each of the ends 16 it is possible to transpose the fan casing so that the placement of the fan casing is in accordance with the rotation direction of the fan, as will be noted in Figs. 1 and 2. The fan casing is bolted to a flat metal disk 19, which is bolted to a bracket 20, this bracket in turn being secured to one of the end members 6. The fan 14 has a series of radial vanes 21 which establish an ample air flow regardless of the rotation direction.

The openings 22 in each end plate of the fan casing 15 provide for influx of material to the fan, the ground material being conveyed from the space 23 in the lower portion of the machine below the hammers to the fan by a curved duct 24. This duct 24 is of circular cross-sectional form at the point of its connection at the fan casing, and changes to an approximate ellipsoidal form at its connection with the hammer housing for the

purpose of providing that a large amount of ground material may be removed readily from the space 23. It will be noticed in Figs. 1 and 2, that the long axis of the ellipsoidal end of the duct 24 is approximately concentrically disposed with reference to the semi-circularly curved perforated screen plate 25 which serves to merely determine the degree of coarseness to which the material is to be ground. Most of the air passing through the fan must pass through the screen 25, carrying the broken particles with it, and in order to realize a high capacity factor, it is essential that the screen be kept constantly cleared of meal or ground material, this being insured by a duct having an elongated opening approximately concentric with the screen. As a further advantage tending towards ready removal of meal, the form of the duct changes from ellipsoidal to circular in a gradual manner and it has been found that this shape of duct permits the use of a radial blade fan of the kind described which operates in either direction, thus avoiding the necessity of employing a fan having tangential vanes which would have to be reversed if the direction of rotation was reversed.

Inasmuch as the size of the perforations of the screen 25 determine the coarseness of the ground product, it follows that some materials after contact with the rapidly revolving hammers and the breaker plate will be broken sufficiently to pass through the screen at a point near the upper end thereof, and in order to prevent clogging the chamber 23 at the point indicated by the character 26 which may occur in coarse grinding the duct 24 is shifted as shown in Fig. 1. In this position the duct presents an end of its ellipsoidal opening nearer the point of possible clogging and thus maintains a strong draft of air through the advanced portion of the screen. This has a double beneficial effect as clogging of the screen results in lowered capacity and further breaks the material to an undesired fineness by reason of the extended contact with the hammers.

The duct is bolted to the fan casing by bolts 27 passing through ears 28 on the end of the duct which have elongated openings. At its lower end it is secured by bolts passing through the ears 28' and interposed between the duct and the end plate 6 is an adapter plate 29, Fig. 5, which is provided with bolt holes 30, corresponding to screw holes 31 in end plate 6 (see Fig. 3). The opening 32 in the plate 29 is at one side of the center of the plate so that if the meal is to be withdrawn at an early period in the grinding stage the plate 29 is placed on the end plate 6 as in Fig. 1, and the duct shifted and secured to the plate 29. If a finer screen is employed, it may be advantageous to shift the duct in order to provide a strong draft

through the latter portion of the screen since there is a tendency for finer meal to travel a longer distance along the inner surface of the screen in which event the position of the duct is indicated by the broken lines in Fig. 2 in which case the plate 29 is reversed to have the opening 32 in alignment with the right hand portion of the symmetrical opening 33 in the end plate 6. The chamber 23 beneath the screen 25 is enclosed by steel sheet wall 23' which acts to properly convey the ground material to the discharge opening 33.

By this construction it will be seen that the mill may be readily re-assembled and adjusted to meet conditions of installation other than those contemplated by the original assembly by simply reversing the upper half of the casing on the lower half, reversing the fan casing and adjusting the discharge duct in the event that the duct has been originally assembled for a certain material. As explained in the specification the discharge duct may be positioned with relation to the discharge opening from the casing to meet the conditions of different kinds of material, so that the purpose therefore of adjustably connecting the duct with the casing is two-fold.

Having thus described my invention, I claim:

1. In a grinding mill, a grinding element capable of rotation in either direction, a non-rotatable grinding element, a feeding device, common means for supporting said non-rotatable grinding element and feeding device, means for supporting said common means such that the position thereof may be reversed, whereby the non-rotatable grinding element and the feeding device may each be positioned on either side of the mill depending on the direction of rotation of said rotatable grinding element, a fan casing connected with the mill, a fan in said casing capable of rotating in either direction with said rotatable grinding element, said fan casing having an offset discharge opening and being reversible to alter the position of said discharge opening to conform with the direction of rotation of said fan.

2. In a grinding mill, a casing formed of a lower stationary member and an upper movable member, a rotary horizontal shaft carried by said lower casing member capable of rotation in either direction, a grinding element carried by said shaft, a grinding plate mounted at one side of said upper casing member, and means for removably connecting said casing members together whereby the upper casing member may be assembled with said grinding plate on either end or the outer sides of the vertical center line of said rotary grinding member, a fan connected with said shaft on the outside of said casing, a fan casing for said shaft having an offset discharge opening, and means for so sup-

porting said fan casing that the position thereof may be reversed.

3. In a grinding mill, a casing formed of a lower stationary member and an upper movable member, a rotatable horizontal shaft carried by the lower member capable of rotation in either direction, a grinding plate carried at one side of said upper casing member, and means for removably connecting the two casing members together whereby the upper casing member may be reversed to position the grinding plate and the feed chute each on either one side or the other of the vertical center line of said rotary grinding member, a fan having radial blades connected with said shaft on the outside of said casing, a fan casing for said fan having an offset discharge opening, and means for reversing the position of said fan casing.

4. In a grinding mill, a main casing, a rotary grinding element in said casing capable of having its direction of rotation reversed, a fan on the outside of said main casing, a fan casing for said fan having an offset discharge opening, each side of said fan casing having an inlet opening, a chute leading from said main casing to said fan casing adapted to be connected with either side thereof, and means for supporting said fan casing such that the position thereof may be reversed.

5. In a grinding mill, a main casing, a rotary grinding element in said casing capable of having its direction of rotation reversed, a fan on the outside of said main casing, a fan casing for said fan having an offset discharge opening, each side of said fan casing having an inlet opening, a chute leading from said main casing to said fan casing adapted to be connected with either side thereof, means for supporting said fan casing such that the position thereof may be reversed, and means for adjustably connecting said chute to both the main casing and fan casing whereby the inlet end of said chute may be positioned at different points with relation to said main casing.

6. In a grinding mill, a main casing, grinding elements therein, a curved grate below said grinding elements, said casing having a discharge opening of an elongated character, a fan casing, a chute connecting said casings, the inlet end of said chute being of an elongated character of less area than the discharge opening of said main casing, and a reversible adapter plate serving to connect the inlet end of said chute with said main casing having an opening corresponding to the area of the inlet opening of said chute.

7. In a grinding mill, a main casing, disintegrating elements in said casing, a curved grate beneath said disintegrating elements, a fan casing, a chute leading from a discharge opening in said main casing below said grate to said fan casing, the discharge opening of said main casing being of greater

width than the inlet of said chute, means for connecting the inlet end of said chute to the main casing at one point or another in the direction of the width of said discharge opening, and means for closing that part of said discharge opening not in registration with the inlet end of said chute.

8. In a grinding mill, a main casing, rotatable disintegrating elements in said casing, a grate formed on the arc of a circle concentric with the axis of rotation of said disintegrating elements, a fan casing, a chute leading from a discharge opening in said main casing below said grate to said fan casing, the inlet opening of said chute being of an elongated character in the direction of its width and said discharge opening being of greater width than the width of said chute inlet, means for connecting the inlet end of said chute to the main casing at one point or another in the direction of the width of said discharge opening, means for adjustably connecting the discharge end of said chute to said fan casing at a point such that the movement of the inlet end of said chute in altering its point of connection with said casing will be such as to be substantially concentric to said grate, and means for closing that part of said discharge opening not in registration with the chute inlet.

In testimony whereof, I have hereunto set my hand this 22nd day of October, 1929.

RICHARD S. IGLEHART.
